UNITED STATES PATENT OFFICE

ANSELM JULIUS WILHELM ERICH BRUNNER, OF ASCONA, SWITZERLAND.

GAME PLAYED ON A BOARD.

Application filed October 31, 1924, Serial No. 746,993, and in Switzerland November 1, 1923.

The invention relates to a game played on a board having a surface divided into squares and having leading men and ordinary men, the latter adapted to follow determined movements of the leading men and to be thereby arranged in groups.

The invention is illustrated on the accompanying drawings in which:—

Figs. 1 and 2 show plan views on the board with leading men and ordinary men arranged in accordance with two different ways of playing.

Fig. 3 is a perspective view of a leading man,

Fig. 4 is a perspective view of an ordinary man,

Fig. 5 shows a diagram of the movements of a leading man,

Figs. 6 and 7 are plan views of ordinary men showing detail modifications.

A board consisting of wood, card-board or a similar material is divided into forty-eight squares *a*. The latter are alternately bright and dark colored. The game is provided with a number of ordinary men *b* which corresponds to the number of squares *a*. The ordinary men are of a flat square shape (Fig. 4) and are also made of wood, card-board or a similar material. The ordinary men are provided on their upper face with a direction mark *c* of white and black colour respectively and extending from the centre of a man towards one corner. The bottom faces of the men are white and black respectively. One white leading man and one black leading man are further provided, the so-called "knights" *d* (Fig. 4). The leading men are inserted in two recesses *f* provided in the ledge *e* of the board, when they are not used. The leading men are ordinarily made of the same material as the board and the men *b*.

Let it be assumed that two parties are playing at the game. One of the parties receives twenty-four men the bottom face of which is white and the white knight and the other party receives twenty-four black men and the black knight. Each party places its knight on an empty square *a* irrespective of the color of the latter.

In Fig. 1, in which the movements according to one manner of playing are indicated, the initial position of the knight *d* is designated with (1) for the black knight and with (I) for the white knight. The further movements of both knights *d* are sub-

jected to definite rules. In Fig. 5 the movements which the knight *d* is permitted to make are diagrammatically indicated, according to the rule that the knight is allowed to jump over one vertical and one horizontal row of squares with each movement on a square having a colour that is different to that square from which the knight starts its movement. The playing parties place successively one man *b* on a square *a* within the reach of the movements of the knight and place their knight *d* on the man previously set. For example a white man is put on position (2) and thereupon a black man is put on position (II). In a similar alternating sequence the two parties cover each a further square with a man. Thereby the knights move along the arrows indicated. They are always placed on the top of the last set man and indicate thus the positions taken up by the parties. The parties endeavor to distribute their men on the board in such a manner that every two men of the same colour are placed in the same horizontal row of squares and at equal distances from the centre line *g*. Such a group of two men of the same colour shall be called a "balance" and is represented in Fig. 1 by the positions (2) and (5), (3) and (6), (4) and (7) of the white men, as well as by the positions (II) and (V), (III) and (VI), (IV) and (VII) of the black men. The party which succeeds in obtaining a balance has the lead and is permitted to move with its knight. The knights may be placed on positioned men of their own colour as well as on men of the opponent's colour, provided that the opponent's knight is not already placed on the respective man. If two men of different colours are in the balance position in the same horizontal row of squares, one of them may be captured by the opponent's knight being placed upon it. The captured man is removed from the board and is returned to its owner and is replaced by a man of the capturing party, whereby the latter has obtained a balance. After all the men have been placed on the board the parties endeavor to arrange their men which are not yet in the balance positions to form balances. To this end balance positions are searched by the knights and are covered by single men of the board which are not yet in balance relation to another man. The party which has first succeeded in arranging all its men in balance positions has won.

The losing party continues the game by itself until it has succeeded to place all its men in balance relations. The number of movements of the knight necessary to that purpose are counted as points in favor of the winner.

With the second manner of playing (Fig. 2) one party is allotted 24 men with the white direction mark and the white knight and the other party receives the same number of men with black direction mark and the black knight. The movements of the knights *d* are subjected to the same rules as stated above with the balance game, the difference being that groups of the direction marks have to be obtained. The groups may be produced with two, three or four men which join each other with their edges in which the direction mark ends. The parties place the men in the usual sequence on squares covered by the movements of the knights and a party may place his men to form groups with his own men or with those of the opponent. Black and white direction marks may thus cooperate to form a group. According to the rules the player which has joined a group may continue to move its knight. For example the white knight starting the game may move from its initial position (1) into the position (2), whilst the black knight moves from the initial position (I) into the position (II). Thereupon the parties cover the positions (3) and (III) successively with men, whereupon the white knight moves into the position (4). In this position a man with a white direction mark is joining to the black man of the position (II). In consequence of the obtained joining the white knight is allowed to continue its movement and he is placed in the position (5). The black knight moves now to the

position (IV) and joins there a group consisting of three men. As a joint has been made the black knight continues its movement and covers successively the positions (V) to (X) in which it joins to groups with the exception of the last position. The party which has obtained the largest number of joints and has therefore placed its men first on the board wins. The losing party continues the game by itself until it has placed all its men. The number of movements required to this end are counted as points in favor of the winner.

Three, four or more parties may play at the game. The number of the squares, which need not be 48, must be a multiple of the number of the players. If several parties play the men and knights allotted to each party must have different colours. Instead of the simple direction marks *c* symbols may be provided on the men as is shown in Figs. 6 and 7. The movements of the knights and the arrangement of the direction marks when placing the men might also be subjected to other rules than those stated above.

I claim:—

1. A game played on a board divided into squares for receiving men, characterized by the feature that the game is provided with leading men and ordinary men, the latter following the movements of the leading men for the purpose of forming groups and the movements being governed by determined rules.

2. A game as claimed in claim 1, characterized by the fact that the ordinary men are provided on one side with a direction mark so arranged that it produces a group with the direction mark of an adjoining man.

ANSELM JULIUS WILHELM ERICH BRUNNER.
